UNITED STATES PATENT OFFICE.

MILTON M. KOHN, OF NEW YORK, N. Y.

ELECTRIC FURNACE.

1,187,630.

Specification of Letters Patent. Patented June 20, 1916.

Application filed May 5, 1914. Serial No. 836,419.

To all whom it may concern:

Be it known that I, MILTON M. KOHN, a citizen of the United States, residing at the borough of Manhattan, in the city, county, 5 and State of New York, have invented an Improvement in Electric Furnaces, of which the following is a specification.

My present invention relates to an electric furnace, and is an improvement upon 10 the construction of an electrical heating apparatus shown and described in Letters Patent No. 1,057,745, granted to me in April 1, 1913.

The objects of my present invention are 15 to so improve the construction of the electric furnaces made in accordance with the disclosure of the patent aforesaid, as to result in economy of construction, hence reducing the cost of the apparatus to the 20 consumer, and also in the efficiency of the improved apparatus over that shown in the patent, so that there is a consequent increase in efficiency and a decrease in the cost of the furnaces.

25 In the present case, as in the furnaces heretofore constructed by me, the apparatus comprises a housing, preferably a plurality of heating units, each fitted with a heating medium and removable from the apparatus 30 with one head thereof, together with means for not only varying the temperature produced in the heater, but also maintaining the same constant at a required degree.

In the apparatus as heretofore construct- 35 ed, and as shown and described in the Letters Patent aforesaid, the housing was made of clay sections, which parts were connected by a suitable binder, the space between the housing and casing being fitted with a 40 separate heat insulator. In my improved electric furnace, the housing is preferably made of a cellular or diatomaceous material or infusorial earth, made in blocks or slabs of suitable configurations for building up 45 the housing of the furnace, which also acts as the heat insulator.

In the furnaces heretofore constructed, the heating units were non-reversible, and furthermore it was necessary to remove a 50 head of the furnace in order to take out any of the heating units. In the present case, the heating units are preferably made reversible, or double sided, and are arranged, as heretofore, to be secured together 55 in alinement to produce the desired heating surface, and the electrical and mechanical

connections are such that the units may be removed with one of the heads of the furnace, or separately and independently of each other as heretofore. 60

In the furnaces heretofore constructed, the heating units were supported directly in the housing, whereas in the present instance, I prefer to employ independent supports for the heating units, which supports are suitably secured in the housing, in the necessary positions, and are adapted to receive the heating units and maintain the same in position. 65

In the furnaces, as heretofore constructed, and as shown and described in the patent aforesaid, the heads of the apparatus are made of refractory material, and broadly perform the function of closing the ends of the apparatus, whereas in the furnace 70 constructed in accordance with my present invention, I prefer to so construct these heads that they are not likely to crack, due to the strains put thereon by reason of the great differences in temperature to which 75 they are subjected, and also in order that they may act as a support or a partial support for the heating units, to which they are usually connected, as hereinbefore stated, that the parts may be removed together, the inner portions of the heads being 80 preferably constructed of pure asbestos, while the outer portions are constructed of a composition of asbestos and cement or similar material. 85

It will furthermore be understood, in the furnaces as heretofore constructed and as shown and described in Letters Patent aforesaid, that the temperature control was effected by a rheostat suitably connected 90 exteriorly of the heating mediums in the apparatus, whereas in my improved construction, I prefer to employ suitable rheostat or resistance coils so connected to or built in the heads or the body or housing 95 of the apparatus as to utilize the heat generated therein, in the furnace itself, and furthermore the rheostat or resistance employed is such that the temperature control may be effected in a like manner, whether 100 the apparatus is used on 110 or 220 volt circuits. 105

In the drawing, Figure 1 is a side elevation and partial central cross section on line 1, 1, Fig. 2, illustrating an electric furnace made in accordance with my present invention. Fig. 2 is an elevation and partial cross 110

section on line 2, 2, Fig. 1. Fig. 3 is a view similar to Fig. 1, illustrating a modified form of the invention. Fig. 4 is a view similar to Fig. 2, showing the modification illustrated in Fig. 3. Fig. 5 is a diagrammatic plan illustrating the electrical connections, the rheostat or resistance coils for controlling the current and consequently the temperature in the furnace. Fig. 6 is a perspective view illustrating one of the blocks forming the heating units. Fig. 7 is a similar view illustrating another form of these blocks. Fig. 8 is a cross section through the rheostat terminal employed in the form of invention as applied to a different type of furnace. Fig. 9 is a transverse section showing a modified form of my invention, and Fig. 10 is a view similar to Fig. 9, showing a still further modification of the invention.

Referring to the drawing, and particularly to Figs. 1 and 2, it will be seen that in carrying out my present invention, I prefer to employ a shell or casing, indicated at 10. This may be made of sheet metal or any other suitable material, and of any required dimensions and shape. At its opposite ends, the shell or casing 10 is provided with heads 11 and 12. The head 11 has an opening, in which a heater door 13 or removable plug is suitably fitted. As illustrated, this door is hinged at 14 and provided with a rod 15 carrying a counter-weight 16, by means of which the door may be maintained in either its normally closed position or in an open position. As hereinbefore indicated, the inner portions of these heads 11 and 12 are preferably made of a suitable fibrous material, such, for example, as pure asbestos, whereas the outer portions of these heads are preferably made of a composition of a fibrous material and a suitable cement. Within the shell of the casing 10, I employ a housing, which is built up of a plurality of suitably shaped blocks 17, made of an infusorial earth or cellular or diatomaceous material. These blocks are so made and placed within the housing that they assume a staggered relationship with one another and may be maintained in position within the housing by use of the tie rods 18 and nuts 19, or otherwise. Surrounding the heads 11 and 12, are annular members 11' and 12', through which the tie rods 18 also pass, in order to secure the blocks 17 in position permanently within the shell 10. It will be understood, however, in some instances, particularly where the furnaces are of small dimensions, the housing made of infusorial earth, cellular or diatomaceous material, may be an integral structure, and in all cases this housing is sufficiently heat insulating to enable me to dispense with the use of the filling material, which I have heretofore employed

as a cover for the housing, to make the same sufficiently heat insulating. As illustrated in this form of the invention, I employ a plurality of angular heat unit supports. In Figs. 1 and 2, the chamber within the furnace is shown as square in cross section, and for this reason, in this form of furnace four of these heat unit supports are employed, one being placed in each corner of the heating chamber. Each of these heat units supports, on its outer side, adjacent the corner, is provided with diverging ribs or flanges 21-22, adapted to be received in recesses provided therefor in the housing blocks 17, so as to maintain the heat unit supports in position within the housing with their outer faces preferably abutting against the adjacent inner faces of the blocks comprising the housing.

On its inner side, each heat unit support 20 is provided with a central longitudinal projection or rib 23, between which and the arms of the heat unit support there are recesses 24, adapted to receive and maintain in position the heating units as hereinafter described. Furthermore, each of these heat unit supports 20 is preferably provided with a bore 25 running longitudinally thereof and also with passages 26, in suitably spaced positions, in the central projection 23, or rib 23, so as to provide communication between the heating chamber and the bore 25, which latter is filled with any suitable material, which, under the influence of heat, or otherwise, will liberate certain gases to prevent the oxidization of the material or substance, indicated at 27, under treatment in the furnace chamber, or to otherwise influence or effect the action of the heat on the material being treated.

Referring particularly to Figs. 5 and 7, it will be seen that the heat units I prefer to employ in my present invention each comprises a plurality of blocks placed in alignment with one another to obtain the necessary extent of heating surface, each block constituting a body portion 28, on the opposite surfaces of which there are series of suitably spaced parallel under-cut grooves, indicated at 29 and 30. At opposite ends, 115 each block is provided with flanges 31, adapted to be received in the recess 24 in the heat unit supports 20. As will be apparent from these figures, the under-cut grooves may be made to run parallel with 120 the end flanges, or at right angles thereto, or in one direction on one side, or in the opposite direction on the other side, or in both directions on the same side, in which instance the grooves running in one direction 125 must necessarily be deeper than those running in the other direction, and in both constructions the end flanges are provided with bores 32, adapted to receive rods by which the blocks, comprising any given heat unit, 130

are secured in alinement with one another, and also the electrical connections between the heating medium employed with the heating unit and suitable terminals are completed.

5 Associated with each heating unit, and threaded through the under-cut grooves therein, I employ a heating medium, such, for example, as coiled resistance wires, indicated at 33.

10 As illustrated in Figs. 1 and 2, the rods 34, by which the blocks comprising each heating unit are secured in alinement and electric circuits through the heating medium completed to suitable terminals, may be carried directly through bores provided for this purpose in the rear head 12 of the furnace, and there provided with suitable nuts for making the necessary electrical connections,

15 20 as hereinafter described. In this construction, the rods 34 permanently secure the heating units to the head 12 and in such a manner that the heating units, together with the head 12, may be simultaneously removed from the furnace by taking out the head, or, as shown in Fig. 3, these conducting and connecting rods 34 may terminate at points within the head of the furnace, which, in this instance, is indicated at 64,

25 30 and at their extremities these rods may be provided with screw threads or taper ends in order to receive the tapped ends of the stem 34', or taper recesses therein which extend to the outer surface of the head, and to

35 40 which necessary electrical connections may be made for placing the heating mediums, associated with the heating units, in an electrical circuit, in which construction, as will be understood, in order to remove the heating units, the stems 34' must be disconnected from the contacts on the outer surface of the rear head and the front head of the furnace removed, when the heating units, with the rods 34 and stems 34', may be withdrawn 45 independently of one another from this end of the furnace. In some cases, the ends of the coils may extend through the head to the exterior electrical connections.

45 50 As shown diagrammatically in Fig. 5, the adjacent connecting rods 34 of the heating units in the furnace are joined together by connecting bars 35, 36 and 37, so as to complete the electric circuit through the heating mediums in these heating units, and also 55 the corresponding connecting bars of adjacent heating units are joined by the connecting bars 38 and 39 with terminals 40 and 41.

50 60 Suitably placed on the rear head of the furnace there are also terminals 42, 43 and 44. The terminal 42 is connected to the terminal 40 by a wire 45, and the terminal 43 is connected to the terminal 41 through a wire 46, in which there is a switch 47. The 65 terminal 44 is connected through a wire 48

with the connecting bar 36, and in this wire 48 there is a switch 49. One terminal of the switch 49 is connected by a wire 50 to a rheostat contact frame 52 which may be suitably connected or secured to the wall of the furnace. The rheostat contact frame 52 may be provided with a plurality of contacts 53, to which the ends of heat coils 53' are connected, as usual. These heat coils 53' preferably extend through suitable recesses provided therefor in the blocks comprising the housing, and consequently the heat generated in these coils, when in use, is utilized in the housing to make the same the more heat insulating and consequently to more readily maintain the desired temperature within the chamber. The other terminal 54 of the rheostat frame 52 is connected by a wire 55 with the other terminal of the switch 49.

70 75 80 85 Associated with the terminals 42, 43 and 44, I employ a socket member 56. To this lead wires 57 and 58 are connected, the lead wire 57 being divided within the socket member and leading to contacts 59 and 60, while the lead wire 58 is connected to a contact 61. These contacts 59, 60 and 61, as will be understood, are fixed within the socket member and are adapted to receive any one of the terminals 42, 43 and 44.

90 95 One terminal of the switch 47 is connected by a wire 62 to the terminal 54 of the rheostat frame 52, while the other terminal of the switch 47 is connected by a wire 63 to a terminal 51 of the rheostat 52.

100 105 110 115 120 125 From the foregoing, it will be understood that by properly placing the socket member and the contact arm of the rheostat frame, as well as the switches 47 and 49, the current may be caused to flow through the heating mediums, either in series of multiple, and to be regulated to obtain the desired temperature, for example, with the switch 47 in the dotted line position, shown in Fig. 5, with the switch open when the socket member 56 is so placed that the terminal 42 bears against the contact 60 and the terminal 43 against the contact 61, the current will flow through the wire 45 to and through the various heating mediums, in series, to the switch 47, through the same, the wire 62, the rheostat frame 52 and coils 53', the wire 63, and thence through the wire 46 to the terminal 43 and contact 61, whereas if the socket member is so placed that the terminals 42 and 43 bear against the respective contacts 59 and 60, and the terminals 44 against the contact 61, while the switches 47 and 49 are swung to the full line positions, Fig. 5, the current will flow in multiple through the heating mediums in the oppositely placed heating units to the connecting bar 36, hence to the switch 49 on the wire 55 to the rheostat frame 52, and coils and thence by the wires 48 and 50 to the terminal 44 and its contact 61.

It will further be understood that when it is not necessary to use the rheostat frame 52 and coils 53' the heating units may be utilized in the same manner by placing the 5 switch 47 in the full line position, as shown in Fig. 5, and the switch 49 in the dotted line position.

From the foregoing it will be appreciated that the heating units being made reversible 10 these members may be readily reversed when the heating medium, in one side thereof, burns out or this side becomes damaged or unfit for use, and that while each heating 15 unit may be similarly wider, the heating unit on the outer side, when in position in the furnace, may, by being suitably connected, be utilized as resistance coils to assist in regulating the temperature of the furnace. It will also be understood that in some instances, one face at least of the heating units 20 may be made blank, that is to have no undercut grooves therein, so as to be utilized as a muffle in a furnace. Also the unit supports, being made of a suitable refractory material, are not liable to break or show appreciable wear in placing the units in position 25 therein or removing the units therefrom, and these heat unit supports are employed because the blocks from which the housing 30 is constructed, being made of infusorial earth or diatomaceous material, is naturally more or less friable and consequently not adapted to long withstand the wear incident to placing in and removing the heating units 35 from their position in the furnace. Due to the friable nature of the material from which the housing is made, it may be necessary, in some instances, to cover the inner surfaces with a layer of fireproof cement.

40 Referring to Figs. 3 and 4, it will be seen that the rear head 64 of the furnace may be fitted with an annular member 65 surrounding the same and forming a rim thereon. This head 64 is also provided with a central 45 portion projecting from the inner side thereof and adapted to extend a predetermined distance within the chamber of the furnace, and to lie between a portion of the ends of the heating units and the corresponding end 50 of the housing so as to partially support the heating units. In this form of the invention, I also employ an annular member or a series of blocks, indicated at 66 and lying between the inner extension of the head 64, 55 and a casing 10. In one or more of these blocks 66 there are recesses provided for the reception of resistance coils 67, the respective ends of which may be connected to bolts 68 and one of these secured to the heating 60 unit circuits by means of a connecting bar 69. As is especially illustrated in Fig. 4, between each of these resistance coils 67 there is a terminal 70, and through and between the terminals 70 a rod 71 extends and is 65 movable, the rod 71 being shifted to either

cut in or cut out any required number of the resistance coils 67, in order to properly control the current and consequently the temperature within the furnace. Also in Fig. 4, I may employ an additional resistance 70 coil 70', one end of which is connected to a bar 71', and the other end to the rod 71, which carries a pivoted spring contact 72' which may be turned up to form a sliding contact with the bar 71', so that the additional resistance coil 70' may be placed in circuit in series with any number of the resistance coils 67.

Furthermore, as will be understood, the electrical connections may be so made with 30 the rod 71 that the additional resistance coil 70' may be cut in or out, depending upon the position of the rod 71, so that the socket member 56 and the plug contacts associated therewith may be dispensed with. 35

I found that heretofore a large percentage of the heat within the chamber of the furnace has been dissipated through the heads of the furnace, and I wish to call especial attention to the advisability of 90 placing the resistance coils, used to control the flow of the current in the heads of the furnace, because, as will be understood, when so placed the heat generated in these coils raises the temperature of the chamber 95 of the heads and consequently decreases the radiation of the heat from the chamber of the furnace to and through the same.

Referring to Figs. 9 and 10, it will be seen that my present invention is applicable 100 to the muffle type of electric furnace. In these figures, the shell of the furnace is indicated at 72. Within this shell the housing blocks 73 are fitted and preferably arranged in a staggered relationship. 105

In Fig. 9, the heating units are shown as semicircular, as indicated at 74 and 75, the heating unit 74 being provided with ribs 77, and the heating unit 75 with similar ribs 76. In both of these ribs there are 110 longitudinal bores to receive and contain the rods 78 for making mechanical and electrical connections, as hereinbefore described in connection with the heating unit supports of the preferred forms of the invention. 115

The heating units 74 and 75 are secured in position within the housing by means of the heating unit supports 79, and 80, provided with recesses to receive the ribs 77 and 76 with their respective heating units, and the heating unit supports are secured in position in the housing by means of the diverging ribs 81 and 82, fitting into spaced recesses provided therefor in predetermined 120 blocks forming the housing, it being understood that when in position, the heating units 74 and 75 complete the heating chamber, which, in this instance, is circular in cross section, each of the heating units be- 125

ing provided with series of under-cut grooves 83 adapted to receive a suitably coiled wire or other heating medium.

By reference to Fig. 10, it will be seen that the lining of the heating chamber may be made of an integral heating unit 84, which is preferably circular in cross section and provided on its exterior, at diametrically opposite points, with ribs 85 and 86, both having bores running longitudinally through the same to receive the rods 87 like the rods 78, as hereinbefore described. These ribs 85 and 86 are adapted to be received in grooves provided for this purpose in heating unit supports 88 and 89, each provided with diverging ribs 90-91, by which they are secured in position in recesses provided to receive these ribs in predetermined blocks forming the housing. In this instance, as in the structure shown in Fig. 9, the heating unit, on its inner surface, is provided with series of spaced under-cut grooves 92 to receive suitably coiled wires or other equally good heating mediums.

As shown in Figs. 1 to 4, inclusive, the furnace therein illustrated may be supported upon suitable legs 93, tied by cross bars 94, and in the forms of the invention shown in Figs. 9 and 10, the shell or casing 72 may be provided with brackets 95 which are connected to suitable standards or supports 96, by means of the bolts and set screws 97.

It will furthermore be understood that while I have herein shown and described my invention as particularly applicable to an electric furnace, it may be utilized wherever possible in all forms of electrical heating apparatus, and also that the heating units may be so shaped that their faces will cause the cross section of the heating chamber to be of any desired configuration, irrespective of the shape of the furnace, and may be made integral or divided as occasion may require.

By particular reference to Fig. 6, it will be understood that when this form of unit block is employed, the undercut recesses 29 or 30, depending upon which face of the block is placed toward the heating chamber of the furnace, may be employed as ventilating spaces by omitting the resistance wires in these undercut recesses which come on the inner side of the unit when placed in position, thus providing for the circulation of air between the units and the adjacent portions of the housing.

I claim as my invention:

1. An electric furnace comprising a casting, a combined housing and heat insulator of diatomaceous material therein, a plurality of heating units of refractory material, a corresponding number of heating unit supports, each provided with ribs adapted to be received in recesses provided therefor in

the housing in order to maintain the said supports in position, the said supports being provided with recesses to receive and maintain in position the said heating units so that each of the same may be removed independently of the others, and a heating medium associated with each of the said heating units.

2. An electric furnace comprising a casting, a plurality of blocks of diatomaceous material arranged in a staggered relationship, a plurality of heating unit supports, each provided with longitudinal recesses in its inner surface, ribs on the outer surfaces of the said heating unit supports, adapted to be received in recesses provided for this purpose in the said housing so as to maintain the said heating unit supports in position, a plurality of heating units adapted to be received and maintained in position in the recesses in the said heating unit supports, and a heating medium associated with each of the said heating units.

3. An electric furnace comprising a casting, a combined housing and heat insulator of diatomaceous material therein, a plurality of reversible heating units made of refractory material, a corresponding number of heating unit supports removably secured in the said housing and adapted to receive and maintain in position the said heating units so that any one of the same may be removed independently of the others, and a heating medium associated with each of the said heating units.

4. An electric furnace comprising a casting, a housing therein consisting of a plurality of blocks of diatomaceous material placed in a staggered relationship, a plurality of heating units of refractory material each consisting of a reversible block, means for securing the members of each heating unit together, a corresponding number of heating unit supports, each being provided with recesses in its inner surface to receive corresponding portions of the said heating units in order that the same may be maintained in a position so that each may be removed independently of the others, ribs on the outer surface of the said heating unit supports, adapted to be received in recesses provided therefor in the said housing, so as to maintain the heating unit supports in position and to make the same removable from the housing, and a heating medium associated with each of the said heating unit supports.

5. An electric furnace comprising a casting, a heat insulating housing of cellular material therein, heating units of refractory material, supports therefor forming the walls of the chamber within the furnace, a heating medium associated with each heating unit, and means for supplying a gas from the walls thereof to the interior of the chamber of the furnace to effect the influ-

ence of the heat on the material under treatment therein.

6. An electric furnace comprising a casing, a heat insulating housing of cellular material within the casing, a plurality of heating units each made of refractory material, a corresponding number of heat unit supports secured in the said housing and each provided with a bore running therethrough, a material placed within the bores of the heat unit supports for emitting a gas under the influence of the heat of the furnace to effect the action of the heat on the material being treated in the furnace, and 10 a heating medium associated with each of the heating units.

7. An electric furnace comprising a casing, a housing of diatomaceous material, composed of a plurality of blocks suitably placed within the casing, a plurality of heating units, each consisting of a series of blocks made of refractory material and placed in alinement, a plurality of heating unit supports secured in the housing and 20 adapted to receive the said heating units so that the same may be removed independently of one another and each having a bore therethrough, a material filling the said bore and each heating unit support, adapted under 25 the influence of the heat of the furnace to emit a gas for affecting the action of the heat on the material treated within the furnace, and a heating medium associated with each of the heating units.

8. An electric furnace comprising a casing, a heat-insulating housing of cellular material therein, a heating unit support, projections extending from the outer surface of the said heating unit support adapted to be received in recesses provided therefor in the said housing to maintain the said heating unit support in position, a heating medium associated with each heating unit, and a plurality of resistance coils located 40 within the confines of the furnace with suitable electrical connections to and from the said heating medium to control the passage of an electric current therethrough and consequently the resultant temperature in the 45 chamber of the furnace.

9. An electric furnace comprising a casing, a heat insulating housing of cellular material therein, a plurality of heating units of refractory material, a corresponding number 55 of heating unit supports, projections extending from the outer surface of each heating unit support adapted to be received in recesses provided therefor in the said housing to maintain the heating unit support in position, a heating medium associated with each of the said heating units, and a plurality of resistance coils located within the confines of the furnace with suitable electrical connections to and from the said heating medium to control the passage of an electric 60

current therethrough and consequently the resultant temperature in the chamber of the furnace.

10. An electric furnace comprising a casing, a housing within the casing built up of 70 blocks of diatomaceous material placed therein in a staggered relationship, a plurality of heating units of refractory material, each comprising a plurality of blocks placed in alinement, a plurality of heating 75 unit supports secured in the said housing and adapted to receive and maintain the said heating units in position therein and each provided with a bore running longitudinally therethrough, a material within 80 the bore in each of the said heating unit supports for emitting a gas under the influence of the temperature of the furnace to affect the action of the heat on the material under treatment in the furnace, a heating 85 medium associated with each of the said heating units, and a plurality of resistance coils within the confines of the furnace, together with electrical connections between the same and the said heating mediums for 90 controlling the passage of an electric current therethrough and the consequent resultant temperature in the chamber of the furnace.

11. An electric furnace comprising a casing, a heat insulating housing of cellular material therein, insulating heads fixed at opposite ends of the said casing, a heating unit of refractory material, a heating unit support secured in the said housing and 100 adapted to receive and maintain the heating unit in position therein, means for connecting the said heating unit to one of the said heads so that the same is removable therewith, and a heating medium associated with 105 the said heating unit.

12. An electric furnace comprising a casing, a heat insulating housing of cellular material therein, insulating heads fixed at opposite ends of the said casing, a heating 110 unit of refractory material, a heating unit support secured in the said housing and adapted to receive and maintain the heating unit in position therein, means for connecting the said heating unit to one of the said 115 heads so that the same is removable therewith, a heating medium associated with the said heating unit, and means for controlling the passage of an electrical current through said heating medium to vary the resultant 120 temperature in the chamber of the furnace.

13. An electric furnace comprising a casing, a heat insulating housing of cellular material therein, a head at the end of the furnace, means for connecting a portion of 125 the head to the said housing to maintain the same in position within the said casing, a plurality of heating units, each made of refractory material, a corresponding number of heating unit supports secured in the hous- 130

- ing and adapted to receive and maintain the said heating units in position therein, means for connecting the said heating units to a portion of one of the said heads, with which 5 the same are removable, a heating medium associated with each of the said heating units, and a plurality of resistance coils placed within the confines of the furnace and electrically connected to the said heating 10 mediums so as to control the flow to an electric current therethrough to vary the resultant temperature in the chamber of the furnace.
14. An electric furnace comprising a casting, a heat insulating housing of cellular material therein, a head at the end of the furnace, means for connecting a portion of the head to the said housing to maintain the same in position within the said casing, a plurality of heating units, each made of refractory material, a corresponding number of heating unit supports secured in the housing and adapted to receive and maintain the said heating units in position and each having a longitudinal bore therein, a material within the bore of each heating unit support 20 adapted under the influence of the heat of the furnace to emit a gas to affect the action of the heat of the furnace on the material under treatment therein, means for connecting the said heating units to a portion of one of the said heads, with which the same are removable, a heating medium associated with each of the heating units, a plurality of resistance coils placed within recesses 25 provided therefor in the walls of the furnace, a contact box having terminals to which the ends of the resistance coils are connected, and means for connecting the said coils and contact box with an electric circuit so as to control the flow of the electric current therethrough to vary the resultant temperature in the chamber of the furnace. 30
15. An electric furnace comprising a casting, a heat insulating housing therein of cellular material, a heating unit of refractory material, a heating unit support secured in the said housing and adapted to receive and maintain the said heating unit in position so that the same may be slidably removed from the furnace, a heating medium associated with the said heating unit, and means for connecting the heating mediums in electric 40 circuits of different voltages so as to control and maintain a uniform temperature within the chamber of the furnace, irrespective of the voltage of the circuit.
16. An electric furnace comprising a casting, a unitary housing and heat insulator of diatomaceous material therein, a plurality of heating units each consisting of a number of blocks of refractory material placed in alinement, means for securing together the members of each heating unit, supports secured in the said housing and adapted to receive and maintain in position the said heating units so that each of the same may be 50 removed independently of the others, a heating medium associated with each of the said heating units, and a plurality of resistance coils placed within the confines of the furnace and electrically connected to the said heating units so as to control the flow to an electric current therethrough to vary the resultant temperature in the chamber of the furnace.
17. An electric furnace comprising a casting, a heat insulating housing of cellular material therein, a head at the end of the furnace, means for connecting a portion of the head to the said housing to maintain the same in position within the said casing, a plurality of heating units, each made of refractory material, a corresponding number of heating unit supports secured in the housing and adapted to receive and maintain the said heating units in position and each having a longitudinal bore therein, a material within the bore of each heating unit support 55 adapted under the influence of the heat of the furnace to emit a gas to affect the action of the heat of the furnace on the material under treatment therein, means for connecting the said heating units to a portion of one of the said heads, with which the same are removable, a heating medium associated with each of the heating units, a plurality of resistance coils placed within recesses 60 provided therefor in the walls of the furnace, a contact box having terminals to which the ends of the resistance coils are connected, and means for connecting the said coils and contact box with an electric circuit so as to control the flow of the electric current therethrough to vary the resultant temperature in the chamber of the furnace. 65
18. An electric furnace comprising a casting, a housing and heat insulator within the casing built up of blocks of cellular material placed therein in a staggered relationship, a plurality of heat units, members having projections thereon adapted to be received in recesses provided therefor in the housing and heat insulator to secure the said members in place and maintain the position of the blocks of cellular material of which the said housing and heat insulator is made, and a heating medium associated with each of the said heating units.
19. An electric furnace comprising a casting, a housing and a heat insulator within the casing, a plurality of heating units, support members secured in the said housing and heat insulator for receiving and maintaining in position the said heating units, a heating medium associated with each of the said heating units, series of resistances within the confines of the furnace and devices associated with the walls of the furnace exteriorly thereof for controlling the passage of an electric current through the said series of resistances.
20. An electric furnace comprising a casting, a combined housing and heat insulator

of cellular material therein, a heating unit support secured in said housing and insulator, a heating medium, and a heating unit adapted to be received in said support and 5 to contain the said heating medium, and made of refractory material to absorb and retain heat, the surface of the heating unit being relatively large compared to that of the heating medium.

10 21. An electric furnace comprising a casting, a combined housing and heat insulator of cellular material therein, a heating unit support secured in said housing and insulator, a heating medium, and a heating unit 15 adapted to be received in said support and to contain the said heating medium, and

made of refractory material to absorb and retain heat, the surface of the heating unit being relatively large compared to that of the heating medium, and resistance coils located within the confines of the furnace with suitable electrical connections to and from the said heating medium to control the passage of an electric current therethrough and consequently the resultant temperature in 25 the chamber of the furnace.

Signed by me this 30th day of April, 1914.

MILTON M. KOHN.
